[57] ABSTRACT

In a preferred embodiment of the present invention, there is provided a carton cut-out sheet including a double (two side-by-side portions) flat-faced strip having an elongated shape with loop handles formed at each of opposite ends and adjacent one of the loop-handle ends, a parallel strip portion being integral therewith extending parallel to the handle-strip portion and the additional strip portion having at each of opposite ends securing latch elements such that

each of the latch elements at each of the opposite ends of the second strip portion are lockable one to the other when folded upwardly to meet one-another, there being a crease line dividing the two parallel strip portions along the area points of connection therebetween, and along the remainder of the lengths of the two parallel strips there being a severance of the strip portions one from the other, and there being transverse width-crease lines extending commonly across both of the strips at spaced-apart points along the axial longitudinal length of the strip portions such as to define corresponding side-by-side separate bottom sections, one each for each of the strip portions, along the severance such that when bent-up along one of the width-crease lines adjacent the area of connection, and when bent (folded) along the dividing crease line, the bottom of the second strip portion is placeable over the upper face of the first strip portion, and upon the bringing together of the opposite loop handles, thereafter the opposite-end latch elements are pullable upwardly and together around the respective handle elements. The result of such construction and the folding thereof is a folded carton such as that shown in FIG. 5, in which by lifting the folded carton by simultaneously both loop handles by the placing of the fingers therethrough, the lifting force serves to support the inner bottom by virtue of the pulling upwardly on the edges of the outer bottom by the respective handle elements, while concurrently the locked latch elements are pulled upwardly whereby the inner bottom also contributes to the lifting and supporting of any contents within the carton.

DISPOSABLE PORTABLE DOUBLE-BOTTOM-LIFT HANDLED CARTON

This invention relates to a new and portable disposable carryout food carton.

BACKGROUND TO THE INVENTION

Prior to the present invention, there have existed numerous types and designs of portable cardboard, plastic or metal cartons for the carrying of drinks, various foods such as chicken, pizza, and the like, particularly as sold in delicatessens, and supermarkets. A major difficulty in the practical use of many of these cartons has been the lack of strength of the carton to support any substantially large or even moderate amount of weight particularly where hot foods are involved which steam or sweat or otherwise wet the bottom of the carton, and similarly the same is true for cold materials which might melt or sweat and wet the bottom of the carton. Sanitation also is a major concern, it being desirable that any carton be so constructed as to substantially exclude outside foreign dirt or other matter that may be upon a surface onto which the carton is placed or set, such as might reach the food through corner crack in the carton. However, of major and controlling importance to the party utilizing such cartons in a business of sending-out foods, the carton while achieving the advantages overcoming or otherwise avoiding the above-type difficulties, must concurrently be of such a design and structure and mechanism of putting the cartons together, that such putting-together may be done in a minimum short period of time and the carton structure must be of very low cost, in order that the send-out food businesses or other food-packaging businesses may work with low cost materials rapidly while attaining the above-desired ends, together with a resulting carton with aesthetically appealing appearance and practical size and carrying facilities, while being disposable in its nature without any consequential economic loss.

SUMMARY OF THE INVENTION DISCLOSURE

Accordingly, objects of the present invention include the overcoming of disadvantages and difficulties of the type discussed above.

Other objects become apparent from the preceding and following disclosure.

One or more objects of the present invention are obtained by the invention as defined herein.

In the present invention, the carton formed is easily put-together from a single sheet strip cut to a predetermined shape which includes substantially two parallel strips joined near one end thereof, with opposite ends of a first one of the strips having handle elements as a part of the shape, and with each of opposite ends of a second strip portion having latching elements as a part of the shape whereby opposite ends may be latched together during the folding of the carton, each of the opposite latch-ends having two latching elements matable with the two latching elements of the opposite end of the second strip portion. Preferably the two strip portions include fold creases extending commonly across both of the strips at points along which the strips are severed from one-another such as to define corresponding bottom areas for each of the parallel strips, and there also being a fold line extending along the line of direction axially aligned with the line of severance

between the severed portion of the parallel strips. By virtue of the preferred and inventive shape of the present invention, it is possible to carry sweaty food materials or wet-type food material with added security 5 against a rupture of the bottom by virtue of a double bottom, together with the fact that by the structure of the present inventive carton, the lifting force is obtained such that each of the double-bottom portions 10 serves to contribute lifting support one independent of the other, relative to the weight of the contents rather than merely one bottom being an absorbant pad without offering any independent lifting-support to the contents. The lifting support of the present inventive carton, when folded into carton form, is by virtue of the 15 turned-up latched ends of the inside-bottom being pulled upwardly when the carton is carried by the handles by virtue of the fact of the latched ends extending huggingly around the handle extensions such as to pull inwardly the handle extension in order that a lifting by 20 the handles causes the handle extensions to pull upwardly on the latched ends, while at the same time the handle extension by their connection to (extension of) the outside bottom edges on opposite edges of the outside bottom pull upwardly on the opposite edges of the 25 outside bottom to thereby cause the outside bottom to support the inside bottom with a lifting force. This relationship can be better understood by reference to the Figures as follow, whereupon the other advantages and fulfillment of the objects of the invention are also obtained.

THE FIGURES

FIG. 1 illustrates an elevation plan view of a cut-out sheet material typically of cardboard, of the shape of a 35 preferred embodiment of the present invention.

FIG. 2 illustrates a still further preferred embodiment in in-part elevation plan view, illustrating an additional flange appendage as extending from an identified corresponding portion to that of FIG. 1, except that in 40 FIG. 2 the portions are identified with "prime" designations for corresponding numerals.

FIG. 3, FIG. 4, and FIG. 5 are perspective views which illustrate the progressive steps and resulting 45 folded carton for the folding of a carton of a preferred embodiment of the above-noted FIG. 2.

DETAILED DESCRIPTION OF THE INVENTION

With reference to the FIG. 1 embodiment, there is disclosed a cut-out sheet of cardboard as cut-out structure 6, having two separate elongated strip portions 7 and 8 extending axially along side one-another in parallel relationship having a severance 19 extending up to point 20 at which a crease line axially aligned with the severance continues for the remaining length of the sheet, on each of opposite sides of the crease line from point 20 there being side portions 10 and 11, and two bottom portions — as designated above as strip portions 7 and 8 — being on opposite sides of the severance 19, and also the side portions 9 and 12 being on opposite sides of the severance 19. Extending from each of opposite axial ends of the strip portion sides 10 and 9 are handle extensions 13a and 13b separated from the respective sides 10 and 9 (as illustrated) by the fold lines 21b and 21a. As a part of each handle extension, there is a shaped handle 14a, and 14b, as illustrated, having annulus space 14c and 14d for a person to place his fingers therethrough for the grasping of the

handles. Similarly at opposite ends of the strip portion ending in side portions 11 and 12, there are latch angularly extending portions 15a, 15b, 16a, and 16b, with respective slits extending in opposite direction for 15a versus 16a, and 15b versus 16b, such that when folded the 15a is latchable with the 16a, and the 15b is latchable with the 16b. The portions —i.e., separate bottom portions 7 and 8 are defined between the fold or crease lines 22b and 22a respectively and between the fold lines 23b and 23a respectively. Although this FIG. 1 embodiment is not shown in the folded state, the FIG. 2 embodiment is identical in all respects to the FIG. 1 embodiment, except that the FIG. 2 embodiment is further preferred in the including of a leg extension portions 26a, 26b, and 26c, having fold lines 27a, 27b, and 27c, and accordingly the FIG. 1 embodiment would be folded the same as indicated for the FIG. 2 embodiment for which the folding into a carton is illustrated in FIGS. 3 through 5.

In the FIG. 2 embodiment, the leg extension portions 26a, 26b, and 26c formed or defined by crease lines 27a, 27b, and 27c, form additional circumscribing sides within the folded carton in the manner shown in FIGS. 3, 4, and 5, a primary benefit being the closing of the otherwise open corner spaces in the folded carton. The parts and/or elements of the FIGS. 2-5 embodiment correspond to the same numerals of FIG. 1, although FIG. 2 numerals are "primed" as 8' versus 8. Accordingly, the FIG. 3 shows the carton after folding upward along lines 22b and 23b, and thereafter folding at the line 20' such that the bottom portion 8' is turned to overlie bottom portion 7'. The handle extensions 9' and 10' are then folded upward and over such that handle loops 14b' and 14a' lie flushly opposing one-another as shown in FIG. 5, whereupon the latch members 15b' and 16b' are locked together, and latch members 15a' and 16a' are locked together at their respective slits 17a', 17b', 18a' and 18b'. Lifting on the handles 14b' and 14a' lift up on the locked latch extensions 15a', 15b', 16a' and 16b', whereby the bottom 8' supports the weight of contents; the upward lifting force on the handle loops pulls up on the walls 10 and 9 and on the bottom 7', thus the bottom 7' supportingly lifting upwardly on the overlying bottom 8'.

It is within the scope of the present invention to make such modifications and variations and substitution of equivalents as would be apparent to a person of ordinary skill.

I claim:

1. A portable container device comprising in combination: a sheet structure having opposite upper and lower substantially flat faces, the sheet structure including two portions separated by a line of severance extending substantially more than half a length of the sheet structure and a first fold line aligned with and in series with the line of severance and extending the remaining length of the sheet structure from the termina-

tion of the line of severance, the first fold line extending the remaining length between the two portions, and including at least two additional third and fourth fold lines spaced apart and parallel to one-another extending across both portions at points where the portions are severed from one-another, the third and fourth fold lines extending the width of the sheet structure, opposite ends of the length of one of the portions of the sheet structure including extensions shaped as opposite-end handle structures, and each of opposite ends of the length of the other portion including extensions shaped to form latching means for latching one end latching means to an opposite end latching means lockably.

2. A portable container device of claim 1, in which each locking means extension includes two diverging leg structures.

3. A portable container device of claim 2, in which each leg structure includes a leg fold line extending transversely across the width of the leg structure on upper and lower surfaces thereof extending from a predetermined outer side edge of the leg to a more distally located predetermined point along an inner side edge of the leg.

4. A portable container device of claim 3, in which there is included a fold line extending transversely across the width of the handle-structures portion, there being such a fold line at each of opposite ends of the handle-structures portion with each handle-structures portion fold line separating each handle-structure extension from the portion from which it extends.

5. A portable container device of claim 4, in which the latching means of opposite ends include oppositely-directed severances extending widthwise across a portion of each respective leg structure such that leg structures of opposite ends are matable along the severed portions thereof.

6. A portable container device of claim 5, in which each handle-structure extension defines an annularly-shaped handle corresponding to that at an opposite of its commonly integral intermediate portion such that the respective opposite-end handles are face-to-face matchable to one-another to facilitate grasping both handle-structure extensions in one hand with the fingers of the hand through the matched annulus space of the two face-to-face handle-structure extensions.

7. A portable container device of claim 6, including a laterally extending flange having opposite parallel sides which when folded serves to provide an inner second and circumscribing enclosing wall within a folded carton structure.

8. A portable container device of claim 1, including a laterally extending flange having opposite parallel sides which when folded serves to provide an inner second and circumscribing enclosing wall within a folded carton structure.
